(57) **CLAIM**

The ornamental design for a tuning peg pendant, as shown and described.

DESCRIPTION

This application is related to U.S. Design application Ser. No. 29/539,548, entitled "Tuning Peg Pendant," and U.S. Design application Ser. No. 29/539,543, entitled "Tuning Peg Cover," filed concurrently herewith, each of which are incorporated herein by reference in its entirety.

FIG. 1 is a front perspective view of a first embodiment of a tuning peg pendant showing my new design;

FIG. 2 is a front perspective view thereof shown in an environment of use;

FIG. 3 is a front elevational view thereof;

FIG. 4 is a right side elevational view thereof, the left side elevational view being identical thereto;

FIG. 5 is a top plan view thereof;

FIG. 6 is a bottom plan view thereof;

FIG. 7 is a front perspective view of a second embodiment of a tuning peg pendant showing my new design;

FIG. 8 is a front perspective view thereof shown in an environment of use;

FIG. 9 is a front elevational view thereof;

FIG. 10 is a right side elevational view thereof, the left side elevational view being identical thereto;

FIG. 11 is a top plan view thereof;

FIG. 12 is a bottom plan view thereof;

FIG. 13 is a front perspective view of a third embodiment of a tuning peg pendant showing my new design;

FIG. 14 is a front perspective view thereof shown in an environment of use;

FIG. 15 is a front elevational view thereof;

FIG. 16 is a right side elevational view thereof, the left side elevational view being identical thereto;

FIG. 17 is a top plan view thereof;

FIG. 18 is a bottom plan view thereof;

FIG. 19 is a front perspective view of a tuning peg pendant showing my new design;

FIG. 20 is a front perspective view thereof shown in an environment of use;

(Continued)

FIG. 21 is a front elevational view thereof;
 FIG. 22 is a right side elevational view thereof, the left side elevational view being identical thereto;
 FIG. 23 is a top plan view thereof; and,
 FIG. 24 is a bottom plan view thereof.
 The broken lines showing a chain in FIGS. 2, 8, 14 and 20 illustrate environment and form no part of the claimed design.

1 Claim, 12 Drawing Sheets

Related U.S. Application Data

which is a continuation of application No. 13/466,080, filed on May 7, 2012, now abandoned.
